UNITED STATES PATENT OFFICE.

WALTER E. BENNETT, OF PORTSMOUTH, NEW HAMPSHIRE, ASSIGNOR TO THE MORLEY BUTTON MANUFACTURING COMPANY, OF SACO, MAINE, AND BOSTON, MASSACHUSETTS.

EYELET-SETTING TOOL.

SPECIFICATION forming part of Letters Patent No. 672,884, dated April 30, 1901.

Application filed October 22, 1900. Serial No. 33,840. (No model.)

To all whom it may concern:

Be it known that I, WALTER E. BENNETT, a citizen of the United States, residing at Portsmouth, in the county of Rockingham and State of New Hampshire, have invented 5 a new and useful Improvement in Eyelet-Setting Tools, of which the following is a specification.

My invention relates to eyelet-setting devices; and its object is to provide a tool adapted for use in eyelet-setting machines or in hand eyelet-setting instruments which shall score or split the end of the tube of the eyelet where the same is to be upset and flanged at regular and equal intervals and shall then upset and flange the end of the tube when it is so split. With the eyelet-setting tools now in use a smooth protuberance or mandrel circular in section and usually 15 tapered enters the end of the tube of the eyelet, spreads and breaks the same, and then an annular shoulder or cup around the base of the protuberance or mandrel forms the flange upon the eyelet. On wedging open 20 the end of the tube of the eyelet the smooth round mandrel breaks or splits the tube in several places and wherever the tube happens to be weakest. As a result when the flange is formed and the eyelet set the breaks 25 in the flange are irregularly and unevenly spaced and are more numerous in some eyelets than in others, causing the work to look more ragged and unsymmetrical than is desirable. These defects are overcome by the 30 use of my invention, whereby the end of the tube of an eyelet may be scored or cut at regular and equal intervals as the mandrel enters it, thus evenly spacing the breaks in each flange and making all eyelets uniform in appearance.

The accompanying drawings illustrate, enlarged, some of the embodiments of my invention.

Like parts are indicated by like letters in all the figures.

Figure 1 is a view of one form of an eyelet-setting tool embodying my invention. Fig. 2 is a vertical longitudinal section of the tool shown in Fig. 1. Fig. 3 shows an eyelet in 50 which the tool is inserted part way and the

scoring or splitting operation is begun. Figs. 4, 5, and 6 are views of modified forms of tools embodying my invention.

As the tool shown in Figs. 1, 2, and 3 is a practicable and serviceable form, I will address my description particularly to that form. The shaft or rod A is adapted to fit into an eyelet-setting machine. B is a mandrel which enters the tube of an eyelet and scores and splits the end of the tube in the manner 60 hereinafter set forth. The mandrel B tapers from its base to its end, being conical in shape at its base or thick end and for about a third of the way out from the base or any suitable distance to insure a complete rounding out of the eyelet when formed, then becoming pyramidal in shape at the middle part and conical again at the small end. The pyramid part may present any number of angles or edges; but I find a hexagonal pyramid 70 best suited for my purpose. Its faces are cut from the cone of which the base part of the mandrel is a frustum, and its edges a a are protractions of the surface of said cone. These edges or projections a a score or cut 75 the end of the tube of the eyelet when the mandrel B is forced into the tube. About the base of the mandrel B is the shoulder or annular cup b for upsetting the end of the tube and forming the flange thereon. The tool is 80 proportioned to the size of the eyelet which it is intended to set. The mode of operation of my eyelet-setting tool is made clear by reference to Fig. 3, in which C is an eyelet of ordinary shape, the mouth of the tube being 85 slightly contracted. When the mandrel B enters the tube the scoring edges or projections a a meet the end of the tube. As the mandrel is forced in farther the scoring edges a a cut or split the tube, as at c c, or by creasing or scoring it so weaken it that when the thick part of the mandrel B enters the latter breaks or splits the tube in the places so creased or scored. The rest of the operation is the same as is usual in eyelet-setting, the 95 end of the tube being upset and the flange formed by the shoulder or cup b by means of pressure.

I do not confine myself to a tool having a mandrel of the precise shape above described,

as it is obvious that my invention is capable of embodiment in many forms, some of which are sufficiently indicated in Figs. 4, 5, and 6. In Fig. 4 the pyramidal portion of the mandrel B extends to the small end. In Fig. 5 the same is true, while the base of the mandrel B is cylindrical instead of conical. In Fig. 6 the entire mandrel is shown as conical, while the scoring edges or projections consist of the peripheral webs or blades *a a*, longitudinally disposed upon the mandrel B. The essential thing is to provide scoring projections on the periphery of the mandrel adapted either to cut the end of the tube of the eyelet or to crease it, so that it will split or break at the desired points. I make the mandrel circular in cross-section at the base and preferably conical, so as to spread the tube of the eyelet. The object of the circular base is to round out the eyelet-hole when the end of the eyelet is upset, since if the pyramidal form is carried to the base the hole of the eyelet set thereby, instead of being round, is polygonal in shape, corresponding to the shape of the mandrel. The diameter of the base, which determines the size and form of the eyelet-hole, should be greater than the greatest diametrical distance between the scoring projections to insure a smooth round eyelet. The tube of the eyelet commonly used is shaped like a frustum of a cone or conoid, and the scoring projections or edges of the tool need project only far enough to score or mark the small end of the tube of the eyelet, so as to weaken it and insure its breaking or splitting at the points of contact with said projections.

What I claim, and desire to secure by Letters Patent, is—

40 1. In an eyelet-setting tool, a mandrel adapted to enter the end of the tube of an eyelet and to spread the same, being circular in cross-section at its base and polygonal in cross-section a short distance above the base.

2. In an eyelet-setting tool, a tapering mandrel conical in shape at its base and pyramidal in shape a short distance above the base. 45

3. In an eyelet-setting tool, a tapering mandrel adapted to enter the tube of an eyelet and to spread the same, said mandrel being circular in cross-section at its base and provided with peripheral longitudinal scoring edges above the base. 50

4. In an eyelet-setting tool, a tapering mandrel, adapted to enter the end of the tube of an eyelet and to spread the same, said mandrel being circular in cross-section at and near the base, and being provided at its smaller part with a plurality of peripheral scoring edges arranged longitudinally upon, 60 and at equal intervals about said mandrel. 55

5. In an eyelet-setting tool, a tapering mandrel adapted to enter the end of the tube of an eyelet and to spread the same, said mandrel being circular in cross-section at its base 65 and provided with peripheral longitudinal scoring edges above the base, the diameter at the base being greater than the greatest diametrical distance between the scoring edges.

6. In an eyelet-setting tool, a tapering mandrel circular in cross-section at its thick end, polygonal in cross-section at its middle part, and circular in cross-section at its small end. 70

7. In an eyelet-setting tool, a mandrel having a base part in the form of a cone, a middle part in the form of a pyramid, the surface of which if produced would be inscribed within the cone of the base, and a tip in the form of a cone the surface of which if produced would be inscribed within the pyramid 80 of the middle part, substantially as described. 75

Signed by me at Portsmouth, New Hampshire, this 19th day of October, 1900.

WALTER E. BENNETT.
